(57) **CLAIM**

The ornamental design for a lace tightening device dial as shown and described.

DESCRIPTION

FIG. 1.1 is a perspective view of a first embodiment of a lace tightening device dial;

FIG. 1.2 is a front view of the first embodiment of the lace tightening device dial;

FIG. 1.3 is a back view of the first embodiment of the lace tightening device dial;

FIG. 1.4 is a right-side view of the first embodiment of the lace tightening device dial;

FIG. 1.5 is a left-side view of the first embodiment of the lace tightening device dial;

FIG. 1.6 is a top view of the first embodiment of the lace tightening device dial;

FIG. 1.7 is a bottom view of the first embodiment of the lace tightening device dial;

FIG. 2.1 is a perspective view of a second embodiment of a lace tightening device dial;

FIG. 2.2 is a front view of the second embodiment of the lace tightening device dial;

FIG. 2.3 is a back view of the second embodiment of the lace tightening device dial;

FIG. 2.4 is a right-side view of the second embodiment of the lace tightening device dial;

FIG. 2.5 is a left-side view of the second embodiment of the lace tightening device dial;

FIG. 2.6 is a top view of the second embodiment of the lace tightening device dial;

FIG. 2.7 is a bottom view of the second embodiment of the lace tightening device dial.

(Continued)

Any broken lines on the figures are for illustrative purposes only and form no part of the claimed design.
